UNITED STATES PATENT OFFICE.

CLARENCE B. WHITE, OF NEW YORK, N. Y.

EXPANDED-METAL STRUCTURE.

SPECIFICATION forming part of Letters Patent No. 670,827, dated March 26, 1901.

Application filed June 23, 1900. Serial No. 21,312. (No model.)

To all whom it may concern:

Be it known that I, CLARENCE B. WHITE, mechanical engineer, a resident of the city of New York, in the State of New York, have invented certain new and useful Improvements in Expanded-Metal Structures for Lathing and other Uses, of which the following is a description accompanied by drawings.

The invention is particularly useful for metallic lathing for fireproof construction of buildings; but it is not limited to such use, as it forms an excellent screen or sieve and is capable of a great variety of uses.

Expanded-metal structures formed by slitting sheet metal and then drawing it apart and expanding it so that the slitted portions form an open-work structure have long been known. Also deeply-corrugated ribs have been formed in such structures, so that when they are secured to the face of a wall or other support by means of the ribs the open-work structure will be held away from and in front of the wall, leaving an interval behind it. Such structures have been termed "self-furring laths." In most instances the expansion of the sheet metal has been in the general plane of the structure, so that all the open-work portion or slatted portion lies in one general plane.

Under the present invention portions of the sheet metal are expanded perpendicularly or transversely to the general plane of the structure. In this way an open-work or honeycomb structure is produced which may, if desired, be several inches in thickness, and which may receive plaster or mortar on both faces and form when supported by vertical rods or wires the center of a partition-wall.

In the accompanying drawings several forms of the invention are shown.

Figure 1 shows a portion of a sheet-metal blank after it has been cut or slitted ready for the formation of the improved expanded-metal structure. Fig. 2 is an edge view of the same. Fig. 3 is an end view of the finished expanded-metal structure. Fig. 4 is a side view of the same. Fig. 5 is a face view. Fig. 6 shows a partial end view of another form of the invention made from the same blank, Fig. 1. Fig. 7 is a face view of the same. Fig. 8 shows a slightly-modified form of blank. Fig. 9 is an edge view of the same. Fig. 10

is an end view of one form of the invention as produced from the blank shown in Figs. 8 and 9. Figs. 11 and 12 show an end view and a face view of a modification or further development of the form of the invention shown in Figs. 3, 4, and 5.

The expanded-metal structure of the present invention is characterized by the opening or expansion of the slitted portions transversely to the general plane of the structure.

The invention is capable of a great variety of embodiments and variations, several of which are illustrated in the drawings. The form shown in Figs. 3, 4, and 5 will be first described, commencing the explanation by a clear understanding of the slitted blank shown in Figs. 1 and 2, from which the expanded-metal structure may be made. Series of slits leaving narrow strips or slats *s* between them are formed at intervals in the metal sheet, leaving unslit portions or ribs *r' r'* between the slitted portions or the slotted sections. Alternate ribs are lettered, respectively, *r r* and *r' r'*. The sheet may be laid on a suitable table, and while holding the ribs *r r* down upon the table the ribs *r' r'* may be forced upward, expanding the slitted portions transversely to the plane of the sheet until the slats *s* assume the positions shown in Figs. 3, 4, and 5. Each slat *s* is bent at two points, as indicated by the short dotted lines *b b* in Fig. 1. In the structure when so expanded the ribs *r r* lie at one side of and beneath the central or general plane *p n* of the structure, and the ribs *r' r'* lie above or on the other side of the plane. The slats *s*, which form the open-work portions, lie transversely to the plane, as clearly seen in the figures. The ribs *r r* have not been drawn away from each other. Neither have the ribs *r' r'* been drawn away from each other; but all the ribs *r' r'* have been drawn away from all the ribs *r r* transversely to the plane *p n*. This form of structure makes a very good sieve for liquids, as the slats *s* are all presented edgewise to the flow of the liquid through the sieve. The most important use for this form of structure is for lathing, as the plaster or mortar finds an excellent open-work to which it can cling firmly.

In the form shown in Figs. 6 and 7 a further expansion transverse to the central plane

p n is shown. The ribs *r''* are raised above the ribs *r'* and the ribs *r* lie below the ribs *r''*, as clearly shown.

The blank shown in Figs. 8 and 9 differs 5 from that shown in Fig. 1 slightly. The inclinations of the successive rows of slits which form the slats *s* are arranged in different order. This blank may be expanded to form the structure shown in Fig. 10, differing slightly 10 from that shown in Figs. 3, 4, and 5.

Any of these expanded-metal structures may be further modified by bending or folding some or all of the ribs *r r'*. For example, in Figs. 11 and 12 a modification of the structure shown in Figs. 3, 4, and 5 is shown, the second, third, fourth, fifth, and sixth ribs being bent, as shown, and a portion of the structure between the second and sixth ribs being thereby rendered thin and flat, as is apparent 15 in Fig. 11. In this form the portions marked *f* in the figures are expanded transversely to the plane *p n*, while the intervening portions lie entirely at one side of the plane *p n*, as shown. This form of the invention is especially valuable for lathing, as the portions *f* 20 may be secured to a wall or other support, as shown in section in Fig. 11, and the intermediate expanded portions be held away from the wall, separated by an interval therefrom, 25 and be adapted to receive and support a comparatively thin layer of mortar or plaster. 30

Having now explained the invention and the principles involved and the valuable technical results obtained thereby, I claim as the characteristic and patentable features of the 35 invention the following:

1. A slotted and expanded sheet-metal structure of alternate slotted expanded portions and ribs, some at least of the slotted portions being expanded transversely to the general plane of the structure, substantially as explained. 40

2. A slotted and expanded sheet-metal structure of alternate slotted expanded portions and ribs, some at least of the slotted portions being expanded transversely to the general plane of the structure, and some of the ribs lying above the general central plane of the structure, and other ribs lying below the said plane, substantially as explained. 45

3. The improvement in art of making expanded-metal structures which consists in displacing alternate ribs between slotted portions in opposite directions relatively to the central plane of the structure, substantially as explained. 50

Signed this 21st day of June, 1900, at New York, N. Y.

CLARENCE B. WHITE.
